UNITED STATES PATENT OFFICE

2,551,383

WOOD BENDING MACHINERY

Karl Michaelis, New York, N. Y.

Application November 2, 1944, Serial No. 561,584

2 Claims. (Cl. 144—263)

1

This invention relates to machines for bending wood and more particularly wood panels and boards, to different radii as desired in each individual case.

In existing wood bending machines bending forms or tools of various radii are required to be mounted in the machine according to the radius desired in each individual case.

In contradistinction to this, devices constructed in accordance with the present invention are fitted with supports, checks or the like which can be adjusted to different relative positions in such manner as to enable wood panels or boards or the like placed thereon or therebetween, and which have been rendered pliable by the action of dry heat, to be bent to any of the many radii for which these supports or checks can be set in the machine. Obviously the provision of such adjustable shaping members renders it easy to change over from one radius to the other and tends to lower the price of the machines.

In the drawings affixed to this specification and forming part thereof an embodiment of this invention is illustrated diagrammatically by way of example.

In the drawings

Figs. 1 and 2 are a front view and a cross-section on the line II—II in Fig. 1, respectively, of a machine for bending long boards or panels to arch form.

In the machine illustrated in Figs. 1 and 2, 80 is a vertical wall, represented here by a metal plate, which is formed with a number of parallel vertical slits 81. In these slits are fitted for vertical adjustment brackets 82 carrying rounded heads 83. Threaded pins 84 extending from the backs of the brackets and carrying nuts serve for fixing each bracket in its slit in the position allotted to it.

85 is a steel plate horizontally arranged on top and to the rear of the wall 80. 86 indicates electrical heating elements arranged underneath the plate 85. 87 are boards which, before being bent, are rendered pliable by the action of the heat accumulating in the steel plate 85. This plate thus functions as a preheating plate such as described in my U. S. Patent No. 2,189,078. 88 is a flexible steel strip of a width equalling or exceeding the length of the bracket heads 83. This strip is heated, for instance, by means of electrical heating elements 89 mounted on its bottom surface.

89 are boards which, after having been preheated on the table 85, were moved into position on top of the steel strip 88 and bent, together with this strip, to the curvature defined by the position of the totality of brackets adjusted in

2

their slits with their head arranged along the desired curve.

The force required to bend the pliable boards may for instance be derived from a motor winch 91, the drum 90 of which projects underneath the table 80 and the brackets. Cables or chains 96 slipped over pins 94 fixed in the ends of the boards and running over sheaves 97 are wound on the drum 90 when the motor is started, and pull the boards down onto the brackets.

I wish it to be understood that I do not desire to be limited to the details shown and described, for obvious modifications will occur to a person skilled in the art.

15 I claim:

1. In a wood bending machine, relatively fixed means arranged on an arc having a convex configuration and constituting a former, a normally planar flexible heat conductive element having 20 heating means affixed thereto, having one face in tangential line contact with said former so as to form a support for a wood blank on its other face and means for exerting a bending force at each end of said blank to move said ends and the 25 underlying corresponding portions of said heater element around said former with the flexible heater interposed between the blank and the former.

2. The wood bending machine of claim 1 30 wherein the relatively fixed means comprises a plurality of adjustably supported checks arranged along said arc.

KARL MICHAELIS.
